THE NORRIS PETERS CO., PHOTO-LITHO., WASHINGTON, D. C.

UNITED STATES PATENT OFFICE.

RICHARD L. HATTERSLEY AND SIMEON JACKSON, OF KEIGHLEY, AND BENJAMIN WALKER, OF BINGLEY, ENGLAND.

LOOM FOR WEAVING AND CUTTING PILE FABRICS.

SPECIFICATION forming part of Letters Patent No. 666,270, dated January 22, 1901.

Application filed March 1, 1897. Renewed November 19, 1900. Serial No. 37,088. (No model.)

To all whom it may concern:

Be it known that we, RICHARD LONGDEN HATTERSLEY and SIMEON JACKSON, residing at Keighley, and BENJAMIN WALKER, residing at Bingley, England, subjects of the Queen of England, have invented certain new and useful Improvements in Looms for Weaving and Cutting Pile Fabrics, of which the following is a specification.

10 This invention relates to improvements in that type of loom for weaving pile fabrics in which the pile is formed by a hooked comb or a series of hooks which periodically engage the pile-warp and hold it while the loops 15 are formed; and the objects of the invention are to enable the loops to be cut and also to improve the mechanism operating the loop forming and cutting devices which is operated by a "dobby."

20 In the accompanying drawings, forming a part of this specification, Figure 1 represents a front elevation of such parts of a loom as are necessary to illustrate the application of our invention. Fig. 2 represents a plan view, 25 and Fig. 3 represents an end view, of the same. Figs. 4 to 11 represent views of details hereinafter referred to.

The hooked comb A, a portion of which is shown on a larger scale in Figs. 4, 5, 6, and 30 7, is mounted on curved arms A² and A³, projecting from the rocking shaft A⁴, mounted in bearings A⁵, formed in the brackets B and B', fixed to the front rail A⁸. The bracket B is continued beyond the shaft A⁴, and its inner end is secured to the side frame B². The arm A² has an extension A⁶ at the back connected by the rod C to the crank-pin C² of the crank C³, fixed on the inner end of the short shaft C⁴, mounted in the bearings B⁴, 40 formed in the side frame B². The short shaft C⁴ is intermittently operated by the gear-wheel C⁵, fixed on the tappet-shaft H³, engaging the gear-wheel C⁶, loosely mounted on the short shaft C⁴, and this latter wheel is intermittently locked to the short shaft by means 45 of the sliding bolt C⁷, fitted in the groove C⁸, formed in the face of the disk C⁹, rigidly fixed on the short shaft C⁴ and lying in the recess E, formed in the projecting boss or hub C' on the 50 face of the wheel C⁶. A lever D is mounted

upon the stud D², fixed in the face of the disk C⁹, and this lever is provided with a slot D³, which engages the pin D⁴, rigidly fixed in the bolt C⁷. A spiral spring D⁵, stretching between the screw D⁶, fixed in the lever D, and the screw D⁷, fixed in the disk C⁹, tends to move the lever D so as to force the upper end of the bolt C⁷ outward and cause it to engage the notch E², formed in the internal periphery of the recess E. Fig. 8 represents a separate view of these parts, with the bolt C⁷ engaging the notch E². The bolt C⁷ is disengaged from the notch E² and is normally held disengaged therefrom by means of the lever E³, which is moved across the path of the stud D⁸, projecting from the end of the lever D, and by arresting the motion of the lever disengages the bolt and stops the shaft C⁴. The lever E³ is pivoted upon the stud E⁴, fixed in the side frame B², and the arm E⁵ of the lever E³ is connected by the rod E⁶ to one end of the lever E⁷, mounted upon the stud E⁸, fixed to the side frame B². The other end of the lever E⁷ is connected by the rod E⁹ to one of the jack-levers of the dobby employed to operate the shedding mechanism.

It has not been deemed necessary to show the dobby, as its construction and application to a loom are well known, and it will be readily understood that each time the shaft C⁴ requires to be operated the dobby is made to lower the rod E⁹, which, through the medium of the connecting parts, disengages the lever E³ from the stud D⁸ and leaves the bolt C⁷ at liberty to engage the notch E², constantly revolving with the wheel C⁶, and locks that wheel to the shaft C⁴. The wheels C⁵ and C⁶ are preferably made eccentric to reduce the speed of the wheel C⁶ at the time the bolt C⁷ engages and disengages the notch E². The rotation of the shaft C⁴ also imparts a longitudinal movement to the shaft A⁴. This is effected by means of the fork F, having projections F² engaging the annular groove F³, formed in the collar F⁴, fixed on the shaft A⁴. The fork F is mounted on the cross-shaft F⁵, mounted in brackets F⁶ and F⁷, secured to the top bracket B. The shaft F⁵ is rocked or operated as required by means of the cam or eccentric C¹⁰ on the short shaft C⁴ engaging the 100

antifriction-roller Y, carried by the arm Y², mounted on the stud B⁶, fixed on the side frame B². The arm Y² is connected by the rod F⁸ to the arm F⁹, rigidly secured to the shaft F⁵.

Fig. 9 represents a separate side view of certain parts of the mechanism operated by the shaft A⁴, and Fig. 10 is a front view of the same.

- 10 The comb A is provided with a double row of hooks a a, and the knife G for cutting the loops is located between them. Immediately before the comb is moved from the next row of loops the knife is brought down to the position shown in Fig. 3 and the separate sectional view Fig. 6, and the loops then upon the hooks are thereby cut, and consequently released from the hooks. To enable this movement to be imparted to the knife, it is mounted 15 upon the studs G², fixed in the arms G³ and G⁴, pivoted upon the studs G⁵, fixed to the arms A² and a⁴ on the shaft A⁴. Figs. 4, 5, and 7 show the parts upon a larger scale. The arm G³ is adjustably connected by the screws 20 G⁶ to the bevel-wheel G⁷. This wheel engages the bevel-wheel G⁸, mounted upon the stud G⁹, fixed to the arm A². The arm H is fixed to the wheel G⁸ and has a projecting stud H², which normally lies concentric with 25 the shaft A⁴, as shown in Figs. 1 and 2. Therefore the comb may be moved to engage the pile-warp without independent movement of the knife G. To depress the knife and at the same time slide it longitudinally so as 30 to produce a smooth cutting movement, the lever H' is provided, having a slot H⁴, which engages the stud H². The lever H' is mounted upon the stud H⁵, fixed to the bracket B, and is connected by the rod H⁶ to the lever H", placed 35 upon the stud H⁸ and also fixed to the bracket B. The lever H" is connected by a rod H⁹ to one of the jack-levers of the dobby, which is arranged to be depressed each time the knife requires to be operated. The arm G⁴ 40 is adjustably connected to the disk g, loosely mounted upon the stud G⁵, fixed in the arm a⁴.
- The comb A is shown in Fig. 3 in the position it occupies after the loops are formed and the intermediate picks of the weft are 45 introduced. Then the loops are cut. To engage the warp again to form the next row of loops, the comb is moved to the position shown by the broken lines a², Fig. 3, when the slay O³ is moved back and the warp e is 50 lifted, and after the hooks a have passed beneath the warp the above-mentioned longitudinal movement is imparted to the shaft A⁴ in order to enable the whole of the pile-warp 55 then lifted to be engaged by the hooks. Then after the hooks are passed back to their normal position the pile-warp is lowered and the intermediate picks of weft are introduced, so as to bind the pile to the fabric as much as possible before the loops are cut.
- 60 It is generally desirable to miss a pick while the looping mechanism is in operation, and for this purpose the loom may be pro-

vided with any ordinary mechanism arranged at suitable intervals to miss a pick at one end and make two picks in succession at the other end, the second pick being made when the shuttle is in the opposite shuttle-box. In the arrangement we prefer for this purpose the cone or antifriction-roller K² on each of the picking-shafts K³ is fixed to the collar K⁴, 70 loosely mounted on said shaft. This collar is connected to the collar K⁵, rigidly fixed below by means of the sliding key-piece K⁶, having two projecting keys K⁷ K⁸, fitting grooves formed in the periphery of the collar K⁴, and the ends of said keys project into notches formed in the upper face of the collar K⁵. Fig. 11 represents a separate sectional view of these parts. To disconnect the picking-shafts from the collars K⁴, the 75 lever L is provided on one side and the lever L² at the other. These levers are each pivoted upon the cross-frame K⁹ and are provided with forked ends L³, engaging grooves K⁹, formed in the said key-pieces. The levers L⁴ and L⁵ are connected together by means of the rod L', and the lever L is connected by the rod L⁴ to the arm t of the lever L⁵, pivoted to the lower back cross-rail K⁹, and its other arm t² is connected by the rod L⁶ to the lever 80 L⁷. The other end of this lever L⁷ is connected by the rod L⁸ to one of the jack-levers of the dobby. The dobby is so arranged that each time a pick is required to be made at the left-hand side of the loom the rod L⁸ is 85 lowered, which, through the medium of the connecting mechanism, operates the levers L and L², thereby disconnecting the picking-cone K² on the right-hand side of the loom and connecting the one on the left-hand side 90 with the picking-shaft, and while they remain thus a pick will not be made on the right-hand side of the loom. On the other hand, a pick is only made at the left-hand side when the cone on the right hand is disconnected from the picking-shaft. The spring L⁹ (stretched between the lever L² and the cross-frame K⁹) is provided to assist in restoring the parts to the position shown when the jack-lever again raises the rod L⁸.

To prevent the weft-fork mechanism from operating the stop mechanism when a pick is missed in this way, we provide a projection N on the spindle N², carrying the weft-fork N³, which projection is engaged by the top of the rod O each time a pick is missed, and the weft-fork is thereby prevented from falling and putting the stop mechanism into operation.

The rod O passes through the top guide O², 125 secured to the front of the slay O³, and is hinged below to the arm O⁴, projecting from the front of the rocking shaft O⁵, mounted in bearings O⁶ O⁶. The shaft O⁵ is vibrated each time the cone is operated by its arm O⁷, 130 connected to the arm O⁸ by the rod O⁹. The arm O⁸ carries an antifriction-roller R, which is kept in contact with the periphery of the cam R² (rigidly secured to the shaft C⁴) by

the spiral spring S. This arrangement is the same as that described in specification of application Serial No. 604,695.

We claim—

- 5 1. The combination with a comb having two rows of hooks, and a knife located between said rows, of mechanism for operating said knife comprising a rock-shaft adapted to have a longitudinal movement and having a projecting arm A² carrying the comb, a rotatable shaft, means for imparting longitudinal movement to the rock-shaft from said rotatable shaft, an arm pivotally connected with the arm A², a bevel-wheel with which the pivoted arm is connected, a second bevel-wheel carried by the arm A² and engaged by the first bevel-wheel, an arm H secured to the second bevel-wheel, the lever H' having a movable connection with lever H and connections between lever H' and a moving part of the loom.
- 10 15 20 25 30 35 40 45 50 55 2. The combination with a comb having two rows of hooks, and a knife located between said rows, of mechanism for operating said knife comprising a rock-shaft adapted to have a longitudinal movement and having a projecting arm A² carrying the comb, a rotatable shaft C⁴, shaft F⁵, fork F on shaft F⁵, an eccentric on shaft C⁴, an arm Y² carrying a roller engaged by the eccentric, the arm F⁹ on shaft F⁵, a rod connecting the arm Y² and arm F⁹, an arm pivotally connected with arm A², a bevel-wheel with which the pivoted arm

is connected, a second bevel-wheel carried by arm A² and engaged by the first bevel-wheel, an arm H secured to the second bevel-wheel, 35 lever H' having a movable connection with lever H and connections between lever H' and a moving part of the loom.

3. The combination with a comb having two rows of hooks, of a rock-shaft A⁴, arm A² thereon, a shaft C⁴, a connection between the latter and the arm, gear-wheel C⁵, gear-wheel C⁶ loose on shaft C⁴, a disk rigid on shaft C⁴, a sliding bolt carried by the disk and adapted to engage and disengage with the wheel C⁶ as set forth, a lever D having a pivotal connection with the disk, a connection between the lever and the bolt whereby the former is adapted to effect the movement of the bolt, a lever E³ adapted to effect the stoppage 50 of movement of the lever, a lever E⁷ with which the lever E³ is connected, and a connection between the lever E⁷ and a moving part of the loom.

In testimony whereof we have hereunto set 55 our hands in the presence of the two subscribing witnesses.
